LIQUEFIED GAS EXPANDER

Donald R. Douslin, Bartlesville, Okla., assignor to
 Phillips Petroleum Company, a corporation of
 Delaware

Application November 16, 1943, Serial No. 510,522

16 Claims. (Cl. 202—160)

This invention relates in general to automatic pressure control of an analytical fractionating apparatus. This invention is particularly applicable, although not necessarily restricted, to the analysis of hydrocarbon gases and liquids or mixtures of hydrocarbon gases and liquids such as natural gas, natural gasoline, gasoline and other petroleum distillates or in fact any mixture of materials which is capable of analysis by distillation under conditions of low temperatures and pressures and especially where the pressure within the fractionating column must be very carefully controlled. The invention relates in particular to the distribution of cooling agent in the condenser section of the column whereby said pressure is controlled. In some respects, the present invention is an improvement on the patent to W. J. Podbielnak No. 1,967,258, issued July 24, 1934. The arrangement described by Podbielnak includes a control device which is adapted to maintain a constant pressure in the column. A manometer which is connected with the vapor outlet tube by a side arm is provided with electrodes leading to an electrical circuit which includes a solenoid valve. The valve controls the effective pressure applied from a source of constant air pressure to a body of liquid air in a flask. In the operation of the Podbielnak arrangement, pressure increase in the fractionating column is registered on the mercury column of the manometer, closing the circuit through the solenoid valve and applying pressure to the liquid air which is forced into the cooling section of the column, thereby reducing the fractionation pressure. The range of pressure change is too broad for accuracy in fractionation of two liquids with close boiling points and varying vapor pressures. My invention is a manifest improvement over the arrangement of the patent in providing fully automatic control of the fractionating pressure in an advantageous and expedient manner and with the elimination of electrical circuits, solenoid valves and other relatively expensive equipment which have heretofore been considered essential to the operation of such devices. My application, Serial No. 468,148, filed December 7, 1942, entitled Automatic pressure control for low-temperature, low-pressure fractionating column, discloses the same form of automatic control that is shown in Figs. 1 and 2 of this application, but is not provided with the liquid gas expander shown in Figs. 3 and 4 which forms a new combination with the other apparatus of Figs. 1 and 2.

While the apparatus of Serial Number 468,148

has been found to give a more uniform pressure in the fractionating column than the Podbielnak patent apparatus, it has been observed that liquefied gases being used as cooling agents will wet the inside of the dispensing tube 5 if the tube becomes colder than a certain definite temperature and it will in the fractionation of certain lighter hydrocarbons. When the dispensing tube is wet by the liquefied gas, the liquefied gas 10 will accumulate at the bottom of the tube and drop at undesired times onto the distilling tube and cause undesired cooling. The effect is harmful to the operation of the pressure control and cooling agent feed device and to the maintenance of a constant pressure. The control of pressure cannot be too accurate, as the principal object is to attain the greatest possible degree of accuracy.

The principal object of the invention is to 20 maintain the pressure in the distilling tube at as constant a pressure as is possible.

Another object is to prevent undesired cooling through the dropping of liquid cooling agent directly on the tube, and to conduct excess cooling agent away from the tube to expand without adversely affecting the operation of the pressure control device.

An important object is to provide a thermal 30 "fly wheel" which will act to average and smooth out temperature changes.

Another object is to provide means for suddenly cooling the tube in spite of the thermal "fly wheel" if pressure in the distilling tube 35 should rise suddenly from any cause, without the cooling agent having to pass through any tortuous path.

Another object is to provide automatic feed of 40 cooling agent in combination with the thermal "fly wheel" so that constant pressure is maintained.

Other objects are to accomplish the desired results with a minimum of cheap, foolproof, simple and accurate apparatus involving a minimum of 45 upkeep, repair and attention in operation.

Numerous other objects and advantages will be 50 obvious to those skilled in the art upon reading the accompanying specification and claims and looking at the accompanying drawings.

In the drawings:

Fig. 1 is an elevational view of the fractionating column, constant pressure control and automatic feed with the liquid gas expander in the cooling zone of the column.

Fig. 2 is an elevational view in cross section of

the floating needle valve and closely related parts with the other parts broken away.

Fig. 3 is an elevational view in cross section of the cooling zone of the column, the gas expander and closely related parts, with parts broken away.

Fig. 4 is a perspective view of the expander.

With specific reference to Figure 1, 1 is an analytical fractionating column of the general type described in Podbielnik Patent 1,967,258, having heating element 2 and a cooling zone 3 forming a receptacle at the top of the column provided with an outlet 4 and inlet conduit 5 connected with a supply 6 of liquid air or nitrogen, which is adapted to be forced by compressed air pressure through conduit 7 into the cooling section in an amount proportionate to pressure variation in the fractionating column in a manner hereinafter described. The overhead vapors from the fractionating process pass through conduit 8 to an accumulator not shown. Conduit 8 is provided with a side arm 9 which connects with a mercury manometer 10 fixed to the meter stick 11. The arm 10A of the manometer connects with conduit 7 and is provided with a floating needle valve designated generally at 12 in Figure 1 and shown in detail in Figure 2. As clearly shown in Figure 2, arm 10A is vented to the atmosphere through air vent 13 and has an elongated relatively restricted section 14 through which the head 15 of the needle valve will barely pass. The needle valve may be formed of any suitable material either solid or hollow according to the specific gravity of the manometer fluid, the main prerequisite being that it floats on the body of fluid in the column. In the present application I prefer to construct the needle valve of solid glass with an enlarged lower portion for contact with the manometer fluid. A constriction 16 is provided in the arm 10A to limit the downward movement of the needle valve. This type of valve with vent 13 is known to the art as a bleed valve.

The arm 10A is provided with a side arm 17 connected with a source of air under constant pressure. It will be understood that the inside diameter of the restricted portion 14 of the arm 10A is slightly greater than the outside diameter of the needle valve head 15, so as to allow a continuous small flow of air through the vent, the magnitude of which is dependent on the position of the needle valve 12. A leveling bottle 18 having a pinch clamp 19 is connected with the manometer tube 10 at the bend thereof.

In Figure 3 a liquid gas expander 20 is shown in cooling zone 3. While the expander could rest directly on the glass I prefer to mount it on spaced cork supports 21, three in number although more or less may be employed. The expander is made preferably of aluminum or copper, which have high specific heats and high thermal conductivity, but of course other materials may be employed, although metals are generally preferable because they are generally the best heat conductors and reservoirs.

The expander has a central bore 22 which may be enlarged at 23 if desired. The exact shape of these bores and of the exterior of the expander is not so important, a slot 24 is cut from bore 22 to the exterior of the expander, and the slot is provided with a lip 25 and a downwardly directed surface 26.

The lower end of tube 5 is preferably bellied out at 27 and is placed opposite lip 25 as shown in Figure 2.

The outlet tube 4 for the spent gases is provided leading out from chamber 23 through cover plate 29 to the atmosphere. A packing 30 is generally provided to form a bottom limit to the cooling zone 3, sealing around distilling tube 31.

In operation, heat is applied to the bottom of the fractionating column and overhead vapors pass through the line 8 to the accumulator, not shown. The pressure variation in the fractionating column is registered on the manometer column fluid which cause the needle valve to rise and fall relative to the restricted portion 14. The quantity of air under constant pressure from air line 17 passing head 15 to the vent 13, and likewise the pressure imposed on the liquid air supply 6, is therefore, a function of the pressure in the fractionating column. It is therefore obvious that increase of pressure in the fractionating column will force an increased quantity of liquid air into the cooling zone 3 reducing the pressure in the column. During normal operation and while the pressure in the column is constant a small quantity of liquid air is continuously forced into the cooling zone. By regulation of the compressed air pressure admitted at 17 and by adjusting the mercury level with the leveling bottle 18 it is possible to fractionate under any desired constant pressure automatically and without attention of the operator.

If the pressure rises suddenly in tube 31 for any reason the liquid gas will gush out of tube 5 across lip 25 and directly contact tube 31 to rapidly bring down the temperature. If the pressure rise is slow however, the liquid gas will flow out of the lower portion of bell 27 and will not cross the lip but will flow down 26 and the outside of expander 20. The expander 20 acts as a reservoir on thermal "fly wheel" and absorbs the shock of the cooling agent, but being a good conductor draws heat out of the tube 31. Any dripping on 26 is also absorbed without shock to the system.

The position of outlet tube 4 is such that all gases in cooling zone 3 must pass close to tube 31 inside the expander 20 on their way out. This insures proper controlled cooling of tube 31. The space between tube 31 and bore 22 allows evaporation of the cooling liquid when it is forced in quantity over lip 25 when fast cooling is necessary.

Besides providing a good surface for the expansion of liquefied gas, the expander 20 also acts as a good conductor and reservoir for the absorption of heat; these characteristics of the expander make it a good device for maintaining a uniform temperature in the vicinity of the distilling tube 31. It is evident from the above description that the expander may absorb and dissipate heat readily thereby maintaining a uniform temperature inside the lower portion of the expander, yet it is so designed at the top so that sudden chilling is possible by the vaporization of a liquefied gas on the surface of the distilling tube 31.

When distilling light hydrocarbons, such as methane, ethane and propane, much of the cooling will be done by vaporization of the liquid cooling agent on the distilling tube 31, but with heavier hydrocarbons most of the cooling will be by heat transfer through the cold expander itself. Through the operation of the control equipment described above all cooling will be such that the pressure in tube 31 is substantially constant at all times.

While only one embodiment of my invention

has been illustrated, it is obvious that many changes may be made without departing from the spirit of my invention the scope of which is set forth in the following claims.

Having described my invention, I claim:

1. In a fractional distilling apparatus the combination comprising a source of fluid under constant pressure, a first conduit connecting said source and a supply of cooling liquid, a distilling column, a metal expander for cooling the upper portion of the column, a second conduit conducting cooling liquid from the supply to the metal expander in response to said pressure, a bleed valve in said first conduit for varying the pressure therein, means to deflect the cooling liquid directly against the distilling column during relatively large rates of flow thereof and to deflect the cooling liquid away from the distilling column during relatively slow rates of flow thereof.

2. In a fractional distilling apparatus the combination comprising a source of fluid under constant pressure, a first conduit connecting said source and a supply of cooling liquid, a distilling column, a metal expander for cooling the upper portion of the column, a second conduit conducting cooling liquid from the supply to the metal expander in response to said pressure, a bleed valve in said first conduit for varying the pressure therein, means to deflect the cooling liquid directly against the distilling column during relatively large rates of flow thereof and to deflect the cooling liquid away from the distilling column during relatively slow rates of flow thereof, a U tube communicating at one end with the distilling column and at the other end with said first conduit, a heavy liquid in the lower part of the U tube responsive to the pressures in the first conduit and the distilling column through the respective ends of the U tube, said bleed valve including a valve head floating in said heavy liquid, whereby the amount of cooling liquid reaching said metal expander is varied so as to keep said pressure in said distilling column substantially constant.

3. A cooling liquid dispenser for a distillation column comprising in combination, a distilling tube, a chamber around the tube forming a cooling zone, a liquid gas expander in the cooling zone comprising a metal body having a relatively high specific heat and relatively high heat capacity, the body having a central bore receiving the distilling tube and a slot leading to the upper portion of the central bore, a lip formed in the body in the slot, a downwardly sloping surface on the body in the slot exterior of the lip, an inlet conduit entering the chamber and having a belled end disposed adjacent the lip whereby cooling liquid is discharged across the lip onto the distilling tube during rapid flow of said liquid, and is discharged down the sloping surface during slow flow of said liquid, and an outlet conduit leading from a portion of the central bore below said lip to the exterior of the chamber.

4. A cooling liquid dispenser for a distillation column comprising in combination, a distilling tube, a chamber around the tube forming a cooling zone, a liquid gas expander in the cooling zone comprising a body having a relatively high specific heat and relatively high heat capacity, the body having a central bore receiving the distilling tube and a slot leading to the upper portion of the central bore, a lip formed in the body in the slot, a downwardly sloping surface on the body in the slot exterior of the lip, an inlet conduit

5 entering the chamber and having a belled end disposed adjacent the lip whereby cooling liquid is discharged across the lip onto the distilling tube during rapid flow of said liquid, and is discharged down the sloping surface during slow flow of said liquid, and an outlet conduit leading from a portion of the central bore below said lip to the exterior of the chamber.

10 5. A cooling liquid dispenser for a distillation column comprising in combination, a distilling tube, a chamber around the tube forming a cooling zone, a liquid gas expander in the cooling zone comprising a metal body, the body having a central bore receiving the distilling tube and a slot leading to the upper portion of the central bore, a lip formed in the body in the slot, a downwardly sloping surface on the body in the slot exterior of the lip, an inlet conduit entering the chamber and having a belled end disposed adjacent the lip whereby cooling liquid is discharged across the lip onto the distilling tube during rapid flow of said liquid, and is discharged down the sloping surface during slow flow of said liquid, and an outlet conduit leading from a portion of the central bore below said lip to the exterior of the chamber.

15 6. A cooling liquid dispenser for a distillation column comprising in combination, a distilling tube, a chamber around the tube forming a cooling zone, a liquid gas expander in the cooling zone comprising a metal body having a relatively high specific heat and relatively high heat capacity, the body having a central bore receiving the distilling tube and a slot leading to the upper portion of the central bore, a lip formed in the body in the slot, a downwardly sloping surface on the body in the slot exterior of the lip, an inlet conduit entering the chamber disposed adjacent the lip whereby cooling liquid is discharged across the lip onto the distilling tube during rapid flow of said liquid, and is discharged down the sloping surface during slow flow of said liquid, and an outlet conduit leading from a portion of the central bore below said lip to the exterior of the chamber.

20 7. A cooling liquid dispenser for a distillation column comprising in combination, a distilling tube, a chamber around the tube forming a cooling zone, a liquid gas expander in the cooling zone comprising a metal body having a relatively high specific heat and relatively high heat capacity, the body having a central bore receiving the distilling tube and a slot leading to the upper portion of the central bore, a lip formed in the body in the slot, a downwardly sloping surface on the body in the slot exterior of the lip, an inlet conduit entering the chamber and having a belled end disposed adjacent the lip whereby cooling liquid is discharged across the lip onto the distilling tube during rapid flow of said liquid, and is discharged down the sloping surface during slow flow of said liquid, and an outlet conduit leading to the exterior of the chamber.

25 8. A cooling liquid dispenser for a distillation column comprising in combination, a distilling tube, a chamber around the tube forming a cooling zone, a liquid gas expander in the cooling zone comprising a body having a relatively high specific heat and relatively high heat capacity, the body having a central bore receiving the distilling tube and a slot leading to the upper portion of the central bore, a lip formed in the body in the slot, a downwardly sloping surface on the body in the slot exterior of the lip, an

inlet conduit entering the chamber disposed adjacent the lip whereby cooling liquid is discharged across the lip onto the distilling tube during rapid flow of said liquid, and is discharged down the sloping surface during slow flow of said liquid, and an outlet conduit leading below said lip to the exterior of the chamber.

9. A cooling liquid dispenser for a distillation column comprising in combination, a distilling tube, a chamber around the tube forming a cooling zone, a liquid gas expander in the cooling zone comprising a body, the body having a central bore receiving the distilling tube and a slot leading to the upper portion of the central bore, a lip formed in the body in the slot, a downwardly sloping surface on the body in the slot exterior of the lip, an inlet conduit entering the chamber and having a belled end disposed adjacent the lip whereby cooling liquid is discharged across the lip onto the distilling tube during rapid flow of said liquid, and is discharged down the sloping surface during slow flow of said liquid, and an outlet conduit leading to the exterior of the chamber.

10. A cooling liquid dispenser for a distillation column comprising in combination, a distilling tube, a chamber around the tube forming a cooling zone, a liquid gas expander in the cooling zone comprising a metal body, the body having a central bore receiving the distilling tube and a slot leading to the upper portion of the central bore, a lip formed in the body in the slot, a downwardly sloping surface on the body in the slot exterior of the lip, an inlet conduit entering the chamber disposed adjacent the lip whereby cooling liquid is discharged across the lip onto the distilling tube during rapid flow of said liquid, and is discharged down the sloping surface during slow flow of said liquid, and an outlet conduit leading to the exterior of the chamber.

11. A cooling liquid dispenser for a distillation column comprising in combination, a distilling tube, a chamber around the tube forming a cooling zone, a liquid gas expander in the cooling zone comprising a body, the body having a central bore receiving the distilling tube and a slot leading to the upper portion of the central bore, a lip formed in the body in the slot, a downwardly sloping surface on the body in the slot exterior of the lip, an inlet conduit entering the chamber disposed adjacent the lip whereby cooling liquid is discharged across the lip onto the distilling tube during rapid flow of said liquid, and is discharged down the sloping surface during slow flow of said liquid, and an outlet conduit leading to the exterior of the chamber.

12. In a constant pressure distillation apparatus, a distilling tube having a heating zone and a cooling zone, heat reservoir means in the cooling zone, and means responsive to small increases in pressure in the distilling tube to supply a cooling agent to the heat reservoir and responsive to larger increases in pressure to supply the cooling agent directly to the distilling tube.

13. In a constant pressure distillation appa-

ratus, a distillation tube having a heating zone and a cooling zone for operation at a desired pressure, heat reservoir means in the cooling zone, a supply of cooling liquid, means responsive to increases in pressure in the distillation tube to furnish cooling liquid to the cooling zone from the supply in quantities directly proportional to the increase in pressure over the desired pressure, and a dispensing means for directing small quantities of cooling liquid to the heat reservoir and directing at least a portion of larger quantities of cooling fluid against the distillation tube.

14. A liquid gas expander for use in heat exchange between a stream of liquefied gas capable of rapid evaporation and a vertical tube, comprising a body having a heat conductivity substantially higher than that of glass and a substantial heat capacity, said body having a bore therethrough for receiving said tube therethrough, said body having a slot therein in one side and entering the upper part of said bore at a point below the top of said body for receiving said stream of liquefied gas, said slot being disposed to deflect a large stream of said liquefied gas to the upper part of said bore, a lip for deflecting said liquefied gas formed in the body in the slot and a downwardly sloping surface on the body in the slot exterior of the lip, said surface of said body forming an evaporating surface for a small stream of said liquefied gas.

15. A liquid gas expander for use in heat exchange between a stream of liquefied gas capable of rapid evaporation and a vertical tube, comprising a body having a bore therethrough for receiving said tube therethrough, said body having a slot therein in one side and entering the upper part of said bore at a point below the top of said body for receiving said stream of liquefied gas, said slot being disposed to deflect a large stream of said liquefied gas to the upper part of said bore, a lip for deflecting said liquefied gas formed in the body in the slot and a downwardly sloping surface on the body in the slot exterior of the lip, said surface of said body forming an evaporating surface for a small stream of said liquefied gas.

16. A liquid gas expander for use in heat exchange between a stream of liquefied gas capable of rapid evaporation and a vertical tube, comprising a body having a bore therethrough for loosely receiving said vertical tube therethrough, the lower portion of said bore being enlarged to provide a chamber for expansion of said gas upon evaporation, a conduit passing through said body and connecting said enlarged portion of said bore with the atmosphere, said body having a slot therein to receive said stream of liquefied gas, a lip for deflecting said liquefied gas formed in the body in the slot and disposed to deflect a large stream of said liquefied gas into said bore and a downwardly sloping surface on the body in the slot exterior of the lip for evaporating a small stream of said liquefied gas.
